UNITED STATES PATENT OFFICE.

HENRY SCHLUETER, OF SCRIBNER, NEBRASKA.

BRIDLE-BIT.

1,130,638.

Specification of Letters Patent.

Patented Mar. 2, 1915.

Application filed July 28, 1914. Serial No. 853,610.

To all whom it may concern:

Be it known that I, HENRY SCHLUETER, a citizen of the United States, residing at Scribner, in the county of Dodge and State 5 of Nebraska, have invented certain new and useful Improvements in Bridle-Bits, of which the following is a specification.

This invention relates to improvements in the class of bridle bits in which the cheek 10 pieces or branches are extended in several different directions from the bit iron, for the purpose of affording a number of places at which the bridle straps and reins may be attached and thereby rendering the bit 15 available for use in several different ways; and particularly to those bits which are adapted for use in a manner to develop jaw-pressure for preventing the animal from gripping the bit between the teeth; or in a 20 manner to develop leverage, by coöoperating with the usual chain strap as in curb-bits; or to serve as a very mild bit, by a certain manner of suspending from the head stall and attaching the reins, which develops a 25 direct pull of the bar against the mouth.

The object of my present invention is to so improve the construction of such a bit that it will be more effective in use as a jaw-clamp bit; that it will be reversible as a 30 curb bit to develop curb effects of different degrees of severity; that it will more accurately locate the straps at the points at which it is desired to attach them; and that it will be neater and more symmetrical in 35 general appearance.

To these ends the invention consists in the features of construction hereinafter fully described and particularly pointed out in the claims.

40 In the drawings forming part of this specification—Figure 1 is an end view, Fig. 2 a front view, and Fig. 3 a plan view of a bit embodying the present invention. Figs. 4 to 7 inclusive are end views of the bit with the bridle and rein straps applied in the 45 several different relations for which the bit is especially designed, in order to develop the several different effects for which the bit is constructed; Fig. 4 showing the jaw-clamp or very severe arrangement; Fig. 5 the 50 mild curb arrangement; Fig. 6 the severe curb arrangement; and Fig. 7 the mild or straight pull arrangement.

The present bit, like bits heretofore 55 known, has main cheek pieces or branches 1 of approximately circular form, swiveled

at the ends of the mouth bar or iron 2, and having at top, the suspending eyes 3 swiveled to the cheek pieces 1, so that when the eyes 3 are suspended by the head straps 4, the 60 cheek pieces 1 may rock inward against the jaws of the animal and force the jaws to open under the tension that is being put upon reins 5, attached to the forward eyes 6, as illustrated in Fig. 4. One feature of 65 the present invention consists in giving to the attaching rims 6^a of the eyes 6, an outward deflection as shown in Figs. 2 and 3, that will develop an initial leverage and start the swinging movement promptly and 70 without requiring undue pull upon the reins 5. The swivels 3^a of the loops 3 are mounted in laterally offset lugs 3^b to prevent encroachment of the swivels upon the jaw space. It has also been proposed to extend 75 the branches or cheeks 1, of a bit of this class, in other directions, as for instance to provide eyes 7 for attachment of the reins as shown in Fig. 7, when a very mild or 80 straight-pull effect is desired. I, therefore, 85 make no claim to this feature *per se*. But another feature of the invention relates to the production of different curb effects, for which purpose the cheeks or branches 1 are further provided with loops 8 opposite the 90 swivel loops 6, and interchangeably adapted to receive either head straps 4 or reins 5, so that the bit may be inverted, and with suitably applied chin strap 9, serve as a mild or short-lever curb as shown in Fig. 5, or 95 the severe or long-lever curb as shown in Fig. 6; the swiveled eyes 3 having the effect of increasing the leverage of the pull when receiving the reins 5 as shown in Fig. 6, and of reducing the same when receiving the 100 head straps and leaving the loops 8 for the reins, as shown in Fig. 5. In order to bring the chin strap in proper relation to the bit iron when the bit is suspended by the swivel, a chin-strap loop 10 is provided adjacent 105 the vertical bar 10^a as shown. When inverted from this position, the bit carries its chin strap in the same loop (but on the rearward walls thereof) as the head straps.

The several attaching and suspending 110 loops are arranged in pairs, at opposite ends of two diameters of the cheeks or branches and separated by quadrants of the circle so as to be reciprocally available for their intended services, and each loop embodies a reduced ring which confines the strap accurately at the circumferential point intended.

It will be noted that in any position there is always a bottom loop for developing curb effects if desired.

I claim:

- 5 1. A bridle bit comprising a bit iron and branches; the branches having suspending loops above the bit iron, jaw-pressing portions in rear of the bit irons, and rein-attaching loops forward of the bit iron, in position to develop a lateral turning of the branches from a pull on the reins and forming increased leverages from the bit iron, and said branches having attaching loops opposite said swivels, whereby the bit may 15 be inverted and made to produce curb effects of different degrees of severity.
2. A bridle bit comprising a bit iron and branches; the branches having suspending loops above the bit iron, jaw-pressing portions in rear of the bit irons, and rein-attaching loops forward of the bit iron, in position to develop a lateral turning of the branches from a pull on the reins and forming increased leverages from the bit iron, 25 and said branches having attaching loops

opposite said swivels, whereby the bit may be inverted and made to produce curb effects of different degrees of severity, vertical bars being provided between the swivel loops and the bit iron, and chin-strap loops being associated with said vertical bars. 30

3. A bridle bit comprising a bit iron and cheek pieces hinged to the ends thereof; each of said cheek pieces being constructed with a reduced suspending loop at each end of its vertical diameter, a pair of rein-attaching loops at opposite ends of its horizontal diameter; the attaching loops on the vertical diameter being at different radial distances from the bit iron, and the bit being adapted to have a chin strap associated with each suspending loop, whereby different degrees of curb-effect may be developed. 35

The foregoing specification signed at Fremont, Nebraska, this 7th day of July, 1914. 40
HENRY SCHLUETER.
